UNITED STATES PATENT OFFICE.

OLIVER HIGGINS AND ALONZO SMITH CONDIT, OF NAPOLEON, OHIO.

DEVICE FOR DRIVING AND BENDING HEADLESS TACKS.

SPECIFICATION forming part of Letters Patent No. 337,061, dated March 2, 1886.

Application filed September 10, 1884. Serial No. 142,601. (No model.)

To all whom it may concern:

Be it known that we, OLIVER HIGGINS and ALONZO SMITH CONDIT, citizens of the United States, residing at Napoleon, Henry county, 5 Ohio, have invented a new and Improved Carpet Fastener and Driver, of which the following is a specification.

The object of this improvement is a device for driving headless tacks to be driven into 10 the floor near the wall, and for bending the same suitably to make them operate as hooks, to be passed through the carpet and hold the same to the floor, and from which the carpet can be readily disengaged without tearing or 15 otherwise injuring its texture. These results are attained by the mechanism illustrated in the drawings herewith filed as part hereof, in which the same letters of reference denote the same parts in the different views.

20 Figure 1 is a perspective view of a tack-driver and carpet-fastener embodying the features of my improvement. Fig. 2 is a side elevation representing a modified construction for the same. Fig. 3 is a vertical section there- 25 of more fully illustrating construction. Fig. 4 is a representation of the tack having a point at each end.

A is the tack having points *a a* at each end. B is a square or round bar, provided with a 30 longitudinal perforation, C, of less length than the tack A, in order that the latter, which is to be inserted in the perforation C, will project therefrom three-eighths of an inch or more—the distance to which it is to be driven 35 into the floor. E is a transverse perforation or slot in the body of the bar B, and extends

through the side of the latter to the longitudinal perforation C, in order to make an entrance thereto for a lip or projection of a spring, D, secured by any suitable means to 40 the side of the bar B.

F is a transverse perforation extending from the side of the bar B across the longitudinal perforation C, for a purpose hereinafter set forth.

In order to use the device the tack A is inserted as far as it will go into the bar B, when 45 the lip of the spring D will bear against and hold the tack in position during the adjustment of the bar B preparatory to driving the 50 tack, which is done by applying blows of a hammer or other suitable instrument to the end of the bar B. When the tack is driven as far as it will go, the bar B is removed and 55 adjusted to the tack with the latter in the transverse perforation F, and the bar B is then used as a lever to bend the tack toward the wall in a suitable manner to be passed through the carpet and hold the same.

Having explained the construction and operation of our improvement, what we claim 60 as new, and desire to secure by Letters Patent, is—

The bar B, provided with the longitudinal 65 perforation C, slot or perforation E, and spring D, and the transverse perforation F, as and for the purpose set forth.

OLIVER HIGGINS.

ALONZO SMITH CONDIT.
